UNITED STATES PATENT OFFICE.

MALCOLM H. BAKER, OF EAST LIBERTY, PENNSYLVANIA, ASSIGNOR TO WESTINGHOUSE ELECTRIC AND MANUFACTURING COMPANY, A CORPORATION OF PENNSYLVANIA.

ALTERNATING-CURRENT ARC-LAMP.

SPECIFICATION forming part of Letters Patent No. 729,114, dated May 26, 1903.

Application filed June 26, 1902. Serial No. 113,211. (No model.)

To all whom it may concern:

Be it known that I, MALCOLM H. BAKER, a citizen of the United States, and a resident of East Liberty, in the county of Allegheny and State of Pennsylvania, have invented certain new and useful Improvements in Alternating-Current Arc-Lamps, of which the following is a specification.

In the well-known Bremer arc-lamp, where-
10 in the arc itself, in distinction from the electrode-points, supplies the main portion of the light, it has been customary to control the shape and stability of the arc by means of blower-magnets, and the same sources of in-
15 fluence have been applied to the arc for the purpose of regulating its resistance and at the same time the resistance of the lamp. This has been accomplished by placing an iron core in proper relation to the electrode-
20 points or the arcng space between them, winding the said core with coarse wire in series with the electrodes and with finer wire placed in a shunt across the arc. The two windings are so arranged as to oppose each
25 other electrically, and the coarse-wire winding is so laid as to magnetize the core with a force attracting the arc—that is to say, when the magnetization of the core due to the current in the coarse-wire winding is largely pre-
30 ponderating over that due to the current in the fine-wire winding the arc will be strongly at-
tracted and will be drawn out into a fan shape, thereby raising the arc voltage. On the other hand, when the magnetization due
35 to the current in the fine-wire winding grows comparatively large the total attraction of the core will be diminished, the arc will re-
cede, and the arc voltage will be decreased. Manifestly these described actions take place
40 in the order named whenever, first, the lamp takes too much current and whenever, sec-
ond, the lamp voltage becomes too high—that is to say, the tendency of the differential ac-
tion of the two coils on the magnetic blow-out
45 core is to keep the resistance of the arc nor-
mal by lengthening the arc when the lamp resistance becomes too small and the current through the coarse-wire winding increases

and by shortening the arc when the lamp re-
sistance becomes excessive and the current 50 through the fine-wire winding increases. This action of a differentially-wound magnet is valuable in certain classes of direct-current service; but it is impossible to use such a de-
vice for alternating-current work, since one 55 of the windings would become a closed trans-
former secondary of which the other winding is the primary. In using such a device in connection with an alternating-current arc-lamp the coil would be burned out and the de- 60 vice would be inoperative.

The present invention relates to means for accomplishing in an alternating-current arc-lamp the same results as those effected by the device described above.

By mounting the series and shunt windings upon separate cores and bringing these cores or extensions thereof into such relation to the arc and to each other that the magnetic fields of the two coils act differentially upon each 70 other I am able to keep the inductive actions of the two windings independent and at the same time to produce a differential magnetic regulating-field for controlling the arc resist-
ance. In other words, I avoid the inductive 75 transformer action which would exist if both coils were mounted upon a common core, and I also obtain the regulation which I desire. In this case, as before, the windings are so connected that the field from the series core 80 attracts the arc, while the field from the shunt-
core, acting in opposition to the other field, cuts down the attraction and causes a short-
ening or receding of the arc.

My invention will be clearly understood by 85 reference to the accompanying drawings, in which—

Figure 1 is a plan, and Fig. 2 an elevation, of a pair of arc-lamp electrodes, the arc be-
tween them, and the series and shunt mag- 90 nets and cores whereby I purpose regulating the arc.

In the drawings the electrodes are illus-
trated at 1, 2, the arc is shown at 3, the series magnet at 4, the shunt-magnet at 5, the core 95 of the series magnet at 6, and the core of the

shunt-magnet at 7. It will be seen that the core 6 of the magnet 4 is formed at each end of the said magnet and is bent at an angle so as to occupy a certain definite relation to 5 the electrodes 1 2 and the arc 3 on opposite sides thereof. The core 7 is similarly bent at the opposite ends of the magnet 5, and one portion of the core is arranged parallel and in proximity to the corresponding part of the 10 core 6. Now in case the arc voltage rises the coil 5 takes more current, while the coil or winding 4 may be assumed to be practically unchanged in this respect, owing to the fact that the lamps are supposed to operate on 15 constant current. The result is that the core 7 is more strongly magnetized, opposing to a greater degree the magnetic field of the core 6 and neutralizing still further the attractive effect of the said core 6. In this way the arc 20 recedes to a position of lower voltage. Should the arc voltage drop, the reverse action would take place, as will be readily understood.

I claim as my invention—

1. In an alternating-current electric-arc 25 lamp, means for regulating the resistance of the arc, such means consisting of two coils each provided with a separate core, one coil being in series with the lamp-electrodes and the other in shunt thereto, and the cores be-

ing so placed as to act differentially upon each 30 other.

2. In an alternating-current electric-arc lamp, means for regulating the resistance of the arc, such means consisting of independent magnetic fields adapted to act differentially upon each other, a coil in series with the electrodes, and the coil in shunt thereto, respectively adapted to energize the said 35 fields.

3. In an alternating-current electric-arc 40 lamp, means for regulating the resistance of the arc, such means consisting of a coil and the core therefor, the said coil being in series with the lamp-electrodes and the arrangement being such that the field of the said 45 core lengthens the arc, a separate coil in shunt to the electrodes and a core for the said coil, the arrangement being such that the field of the shunt-core tends to shorten the arc, the two cores being so located that their fields act 50 in opposition to each other.

Signed at New York, in the county of New York and State of New York, this 18th day of June, A. D. 1902.
